(57) **CLAIM**

The ornamental design or an animal pessary, as shown and described.

DESCRIPTION

FIG. 1 is a front perspective view of an animal pessary showing my design;

FIG. 2 is a front view thereof;

FIG. 3 is a rear view thereof;

FIG. 4 is side view thereof;

FIG. 5 is a side view opposite that shown in FIG. 4;

FIG. 6 is a bottom view thereof;

FIG. 7 is a top view thereof; and,

FIG. 8 is a top view of the animal pessary of FIGS. 1-7, shown in an exemplary environmental view inserted in an animal subject.

The dash-dash-dash broken lines shown in the drawing views are included for the purpose of illustrating portions of the animal pessary that form no part of the claimed design. The dash-dot-dash-dot broken lines shown in the drawing views define the boundary of the claimed design.
